UNITED STATES PATENT OFFICE.

LOUIS G. FRANK, OF SAN DIEGO, CALIFORNIA.

PASTRY-CUTTER.

1,182,469.

Specification of Letters Patent.

Patented May 9, 1916.

Application filed June 7, 1915. Serial No. 32,662.

To all whom it may concern:

Be it known that I, LOUIS G. FRANK, a citizen of the United States, residing at San Diego, in the county of San Diego and 5 State of California, have invented new and useful Improvements in Pastry-Cutters, of which the following is a specification.

This invention relates to pastry cutters for cutting biscuit, cakes, doughnuts and the 10 like, and it has particular reference to a rotary cutting device by means of which at a single operation a plurality of cakes or biscuits may be cut.

The present invention has for its object 15 to produce a rotary biscuit cutter of simple and improved construction and particularly to simplify and improve the manner of connecting a plurality of cutting members with a pair of side members or hub members 20 mounted for rotation on an axial shaft.

A further object of the invention is to simplify and improve the construction and assemblage of the parts of the device.

With these and other ends in view which 25 will readily appear as the nature of the invention is better understood, the same consists in the improved construction and novel arrangement and combination of parts which will be hereinafter fully described 30 and particularly pointed out in the claims.

In the accompanying drawing has been illustrated a simple and preferred form of the invention, it being, however, understood that no limitation is necessarily made to the 35 precise structural details therein exhibited, but that changes, alterations and modifications within the scope of the claims may be resorted to when desired.

In the drawing,—Figure 1 is a side view 40 of a pastry cutter constructed in accordance with the invention. Fig. 2 is a top plan view, showing a plurality of cutting wheels mounted for rotation on a single axial shaft. Fig. 3 is a plan view of one of the strips 45 from which the cutters are made. Fig. 4 is a side view of one of the hub members. Fig. 5 is a perspective detail view showing parts of two members and a cutting member assembled therewith.

50 Corresponding parts in the several figures are denoted by like characters of reference.

The improved cutting wheel is composed of two side members or hub members 15 with which a plurality of cutting members 55 C are connected. Each hub member consists of a circular disk or plate of sheet

metal provided at equidistant points around its circumference with notches 16 forming lips 17, the outer ends of which are trimmed so as to present triangular points 18. Each 60 cutting member is formed from a strip of sheet metal 19 having a serpentine edge 20 by bending said strip to form a circular ring, the ends of which are connected together by solder or in some similar convenient manner. The cutting edge will thus present diametrically opposite projecting portions 21, and intermediate said projecting portions there will be shallow or recessed portions 22. The rings or cutting 65 members C are assembled with the hub members 15 by inserting the straight edges thereof into the notches 16, causing the lips 17 to lie adjacent to the inner faces of the rings, which latter are now secured in position by means of solder, as shown at 23. It will be understood that the disks or hub members 15 do not constitute cutters, said 70 disks serving for the purpose of assembling the cutting members C which latter, when 75 assembled in the manner described, project materially beyond the edges of the disks 15, which latter, when the device is in operation, will not cut the dough into strips or small bits. A plurality of the circular cutting members will in this manner be assembled with each pair of hub members to 80 produce a wheel which is mounted for rotation on an axial shaft 24, the ends of which are provided with handles which may be in 85 the form of eyes or loops 25.

As seen in Fig. 2, a plurality of cutting wheels may be mounted side by side on a single axial shaft, thus producing a device 90 of any desired capacity for use in restaurants, bakeries and other places where large quantities of pastry are required to be made. For household or family use, a single wheel will usually be considered sufficient.

The manner of using the improved pastry 100 cutter will be readily understood.

After folding a sheet of dough to the requisite thickness, the handles at the ends of the axial shaft are grasped by the operator, and the wheel or wheels will then be 105 rolled over the sheet of dough, sufficient pressure being exerted to cause the cutting members to cut through the dough, and thus producing a number of cakes or biscuits at a single operation of the device.

110 The device is simple in construction, durable and inexpensive to manufacture.

Having thus described the invention, what is claimed as new, is:—

1. A pastry cutter comprising a pair of hub members consisting of circular disks provided with circumferentially disposed notches and equidistant lips formed thereby, in combination with circular cutting members engaging the notches to present the lips adjacent to the inner faces of the cutting members, and means whereby the parts are securely assembled and means whereby the device may be operated.

2. A pastry cutter comprising a pair of hub members consisting of circular disks provided with circumferentially disposed notches and equidistant lips formed thereby, in combination with circular cutting members engaging the notches to present the lips adjacent to the inner faces of the cutting members, and means whereby the parts are securely assembled, and an axial

shaft on which the circular disks are mounted, said shaft being provided with terminal handles.

3. A pastry cutter comprising an axial shaft having terminal handles and a plurality of cutting wheels supported for rotation on said shaft between the handles, each wheel comprising a pair of circular disk-like hub members having circumferentially disposed tongues, circular cutting members interposed between the hub members in engagement with the tongues and serving to space the hub members apart, and means for securely assembling the hub members and the cutting members together.

In testimony whereof I affix my signature in presence of two witnesses.

LOUIS G. FRANK.
